UNITED STATES PATENT OFFICE.

HENRY G. ELFBORG, OF CHICAGO, ILLINOIS.

GUARD-RAIL.

1,068,975.

Specification of Letters Patent. Patented Mar. 3, 1914.

Application filed November 20, 1911. Serial No. 631,262.

To all whom it may concern:

Be it known that I, HENRY G. ELFBORG, a citizen of the United States, residing at Chicago, in the county of Cook and State of Illinois, have invented certain new and useful Improvements in Guard-Rails, of which the following is a specification.

The object of my invention is to provide an improved guard rail to be used in accordance with the general practice in front of facing point switches, around curves and opposite frog points for the purpose of preventing derailment of rolling stock.

My improved guard rail is an integral structure as distinguished from the structures in common use which are built up from stock rails.

Preferably my guard rail is constructed of manganese steel, but the invention is not necessarily limited thereto and may be formed of any material capable of withstanding the shocks to which it is subjected in practice.

The particular object and nature of the invention will more clearly appear from the following description and claims, taken in connection with the accompanying drawings, in which—

Figure 1 is a plan view of my improved guard rail showing a fragment of a traffic rail and the underlying ties assembled therewith. Fig. 2 is an elevation of my improved structure from the inner side. Fig. 3 is a similar elevation from the outer side. Figs. 4, 5 and 6 are transverse sections on the lines 4, 5 and 6, respectively, of Fig. 1. Fig. 7 is a perspective view of a wedge and of part of the guard rail structure cooperating therewith.

The guard rail structure comprises a guard wall designated generally by the numeral 1, this guard wall being made up of a head 2 supported upon a web 3. The web 3, as shown, slopes inwardly, that is, toward the center of the track from the head 2 and in horizontal section is of a sinuous or wave form as shown in dotted lines in Fig. 1. The web 3 curves alternately to the outer and inner sides of the head 2, and its sinuous form, together with its inward slope from the head 2 to the base 4 results in placing the material of the web in the most favorable position to withstand the shocks upon the head 2, thereby preventing the guard wall from being bent or fractured. The outward slope of the web 3 is also of

advantage in that the base of the web is thereby spaced inwardly from the traffic rail a sufficient distance to permit the use of spikes along the edge of the inner base flange of the traffic rail. This is of especial importance as the traffic rail opposite a guard rail, especially upon curves, is apt to become tilted and loosened unless secured by spikes along its inner edge. A further advantage resulting from the use of the sloping web 3 arises from the fact that in interurban railway track construction, the throat or space between the guard rail and traffic rail is narrower than in standard railway construction. By sloping the web 3 as herein described the throat may be made as narrow as necessary without bringing the lower part of the web too close to the traffic rail.

Extending outwardly from the base 4 are projections 5. These projections in the form illustrated in the drawing extend outwardly from the base plate between the ties at each alternate tie-separating space, and at their outer ends the projections 5 have longitudinal arms 6 overlying the adjacent ties. The arms 6 extend outwardly beyond the outer base flange of the traffic rail 7 and are provided with inclined slots 8, the inclination and length of these slots being such that they are adapted to receive a traffic rail holding spike in any of the positions to which the traffic rail needs to be adjusted. The inclination and length of the slots also are sufficient to enable the device to be used with traffic rails having different widths of base. Near their outer edges the arms 6 are provided with upwardly projecting lugs 9 having inclined inner faces 10, which are preferably, though not necessarily, corrugated. Wedges 11 having correspondingly inclined faces 12, which also are preferably corrugated, are adapted to lie between the lugs 9 and the edge of the outer base flange of the traffic rail. The wedges 11 are provided with spike holes or openings 13 shown in the present instance in the form of notches in the inner sides of said wedges. Near their inner edges the arms 6 are provided with spike holes 14 elongated transversely of the track in order to receive spikes in any one of a plurality of positions in order to accommodate rails in various positions and rails having different widths of base flange. The base plate 4 is also provided with spike holes 15 adjacent its inner edge and the base

plate is preferably recessed at 16 over the spaces between the ties in order to lighten the structure. Similar recesses 17 are also preferably provided at the opposite side of the structure between the arms 6.

In assembling the device, the guard rail structure, which is formed integral throughout, is placed in position upon the ties 18 and there secured by means of spikes. The traffic rail 7 is placed in the position illustrated in Fig. 1, upon the arms 6 of the projections 7 and the wedges 11 are adjusted between the lugs 9 and the outer base flange of the traffic rail. The inclined faces 10 and 12 upon the projections 9 and wedges 11 permit the wedges to be adjusted in such position as to secure the proper track gage. In the event that the inclined faces of the lugs and wedges are corrugated, the corrugations may be so proportioned that movement of the wedge a distance equal to one corrugation will adjust the rail a predetermined amount—say an eighth of an inch. By the use of the wedges 11 in connection with the lugs 9 the outward thrust upon the traffic rail is transmitted through solid metal to the guard rail structure without imposing any bending stress upon the spikes, as is the case when the spikes pass through an enlarged opening in the base plate without lateral support above the ties. The inclination of the slots 8 permits the driving of a spike through the opening 13 of the wedge and said slot in any adjusted position of the wedge, and the transverse elongation of the spike holes 14 along the inner edges of the arms 6 permits the driving of spikes to secure the inner base flange of the traffic rail in any of its adjusted positions. Preferably the projections 5 are strengthened by transverse ribs 20 extending downwardly therefrom and lying between the ties.

The use of the wedges 11 in connection with the lugs 9, as above stated, has the effect of transmitting the outward thrust upon the traffic rail to the guard rail structure through an all-metal construction, whereby the outward thrust upon the traffic rail is resisted by all of the spikes holding the guard rail structure to the ties and no bending stress is imposed upon the spike at the outer edge of the traffic rail. The particular form of the transverse extensions, comprising the projections 5 and arms 6, is such as to secure a rigid connection between the guard rail and traffic rail, at the same time providing, in effect, tie plates for the traffic rail, with the use of a minimum amount of metal.

While I have described a specific form of my invention, it will be understood that the principle may be applied without adhering to the precise form illustrated and described.

It will be noted that part of the slots 8 and the inner surfaces of part of the lugs 9

incline in one direction and the remainder in the opposite direction. By means of this arrangement the structure effectually prevents creeping of the traffic rail longitudinally. Any tendency to creep in either direction has the effect of tightening part of the wedges 11 and thereby more firmly clamping the rail.

I claim:

1. In a device of the class described, a guard wall, a base plate integral therewith, said base plate having transversely extending projections adapted to project beneath a traffic rail between the ties, and longitudinal extensions at the outer ends of said arms, said extensions being adapted to overlie the adjacent ties beneath the traffic rail.

2. In a device of the class described, a guard wall, a base plate integral therewith, said base plate having T-shaped integral extensions, the stems of said T-shaped extensions being adapted to lie between adjacent ties and the arms thereof being adapted to project over said adjacent ties to support a traffic rail.

3. In combination, supporting ties, a guard rail structure comprising a guard wall having an integral base plate, said base plate having projections extending outwardly therefrom between the ties and each of said projections having longitudinally extending arms resting on said adjacent ties, and a traffic rail supported on said arms.

4. In combination, supporting ties, a guard rail structure comprising a guard wall having an integral base plate, said base plate having projections extending outwardly therefrom between the ties at each alternate tie separating space and each of said projections having longitudinally extending arms resting on said adjacent ties, and a traffic rail supported on said arms.

5. In a device of the class described, a guard wall, a base plate integral therewith, integral projections extending outwardly from said base plate and adapted to lie between the ties, longitudinal arms at the outer ends of said projections adapted to overlie the adjacent ties, adjustable means for securing said arms and the outer base flange of a traffic rail to the ties, and means for securing the inner base flange of said traffic rail to the ties.

6. In a device of the class described, a guard wall, a base plate integral therewith, said base plate having transverse extensions, lugs projecting inwardly from said extensions, said lugs having inclined inner faces, wedges adapted to lie between said lugs and the outer base flange of a traffic rail, each of said wedges having a spike hole adapted to register in a plurality of positions with a spike hole in one of said extensions.

7. In a device of the class described, a

guard wall, a base plate integral therewith, said base having transverse extensions, lugs projecting upwardly from said extensions, said lugs having inclined inner faces, wedges 5 adapted to lie between said lugs and the outer base flange of a traffic rail, each of said wedges having a spike hole, and said extensions having spike slots extending in a direction parallel to said inclined inner faces 10 of said lugs.

8. In a device of the class described, a guard wall, a base plate integral therewith, said base having transverse extensions, lugs projecting upwardly from said extensions, 15 said lugs having corrugated inclined inner faces, wedges adapted to lie between said lugs and the outer base flange of a traffic rail, each of said wedges having a corrugated face and a spike hole adapted to register in a 20 plurality of positions with a spike hole in one of said extensions.

9. In a device of the class described, a guard wall comprising a head, a web of less thickness than said head and integral therewith, said web being of sinuous form in 25 horizontal section and curving alternately to the outer and inner sides of said head, a base plate integral with said web, said base plate having extensions adapted to project beneath and beyond the base of a traffic 30 rail.

10. In combination, supporting ties, a guard rail structure comprising a guard wall having an integral base plate, said base 35 plate having projections extending outwardly therefrom between the ties at each alternate tie separating space and each of said projections having longitudinally extending arms resting on the adjacent ties, 40 lugs projecting upwardly from said arms, said lugs having corrugated inclined inner faces, wedges adapted to lie between said lugs and the outer base flange of a traffic rail, each of said wedges having a corrugated 45 outer face and also having a spike hole, and said arms having spike slots extending in a direction parallel to said inclined inner faces of said lugs.

11. In an integral guard rail structure, a 50 guard wall comprising a head, web and base, said web sloping inwardly from said head to said base, and being reversely curved in vertical section.

12. In a device of the class described, a 55 traffic rail and ties, an integral guard rail structure comprising a base, a guard wall sloping upwardly and outwardly from said base at a point inside of said traffic rail thus leaving sufficient space between said base and 60 traffic rail for spikes engaging the inner edge of the base of said rail and said ties, projections extending outwardly from said base between the ties, and longitudinal ex-

tensions at the outer ends of said projections underlying the traffic rail over the ties. 65

13. In a device of the class described, a traffic rail and ties, an integral guard rail structure comprising a base and guard wall, projections extending outwardly from said base, lugs projecting upwardly from said 70 base a distance substantially equal to the thickness of the base of said traffic rail, a wedge between said lug and the base of said traffic rail, said wedges and projections having spike holes adapted to register in a 75 plurality of positions.

14. In combination, supporting ties, a guard rail structure comprising a guard wall having an integral base plate, said base plate having projections extending outwardly therefrom between the ties at each alternate tie separating space and each of said projections having longitudinally extending arms resting on the adjacent ties, 80 lugs projecting upwardly from said arms, 85 said lugs having inclined inner faces, wedges adapted to lie between said lugs and the outer base flange of a traffic rail, each of said wedges having a spike hole, and said arms having spike slots extending in a direction parallel to said inclined inner faces of said lugs.

15. In a guard rail structure, a guard wall, a base plate integral with said guard wall and having parts adapted to project outwardly beyond the base of a traffic rail, oppositely inclined shoulders on said projecting parts of said base, and wedges adapted to be inserted from opposite directions between said shoulders and the outer side of 100 a traffic rail, whereby a tendency of said traffic rail to creep in either direction will tighten one of said wedges.

16. In a device of the class described, a traffic rail, a guard rail having a base underlying and projecting outwardly beyond 105 said traffic rail, oppositely inclined shoulders on said base outside of said traffic rail, and wedges between said shoulders and said traffic rail whereby a tendency of said traffic 110 rail to creep in either direction will tighten part of said wedges.

17. In combination, a traffic rail, a guard rail having a base plate underlying and extending outwardly beyond said traffic rail, 115 said outwardly extending part of the guard rail having a surface inclined longitudinally of said traffic rail, and a wedge adjustable between said inclined surface and said traffic rail. 120

In testimony whereof, I have subscribed my name.
